UNITED STATES PATENT OFFICE.

HENRY D. GRIMES, OF CLEVELAND, OHIO.

LOCK.

1,372,020.

Specification of Letters Patent. Patented Mar. 22, 1921.

Application filed April 30, 1919. Serial No. 293,701.

To all whom it may concern:

Be it known that I, HENRY D. GRIMES, a citizen of the United States, resident of Cleveland, county of Cuyahoga, and State 5 of Ohio, have invented new and useful Improvements in Locks, of which the following is a specification, the principle of the invention being herein explained and the best mode in which I have contemplated applying that principle, so as to distinguish it 10 from other inventions.

My invention relates to locks and particularly to an improvement in dead or dormant locks, *i. e.*, the bolt or bolts are actuated in 15 both directions by manually operated means and not in one direction by automatically operating means such as springs. More particularly, my invention relates to locks in which two movable bolts are provided, 20 the actuation of one bolt resulting in the locking and unlocking of the keeper and the actuation of the other bolt resulting in the separation or bringing together of the keeper and the coöperating locking means.

25 The annexed drawings and the following description set forth in detail certain means embodying my invention, the disclosed means, however, constituting but one of the various mechanical forms in which the 30 principle of the invention may be applied.

In said annexed drawings:

Figure 1 represents a side elevation of my improved lock, showing the same in closed position, the cover being removed;

35 Fig. 2 represents a side elevation in which the lock is in an open position;

Fig. 3 represents a vertical section taken in the plane indicated by the lines III—III, Fig. 1;

40 Fig. 4 represents a horizontal section taken in the plane indicated by the line IV—IV, Fig. 1;

Fig. 5 represents a view similar to Fig. 1 of a fragmentary portion of the lock, the 45 tumblers being removed;

Fig. 6 represents an elevation taken from the plane indicated by the line VI—VI, Fig. 2;

Fig. 7 represents a view similar to Fig. 2 50 of a fragmentary portion of the lock from which the tumblers have been removed;

Fig. 8 represents a side elevation of the lock closed, various elements being shown

retained thereby which it is desired shall not be removed or tampered with by un- 55 warranted persons;

Fig. 9 represents a fragmentary elevation in which one set of two sets of tumblers has been actuated by the key through a portion of their path of movement, resulting in a 60 beginning of the unlocking movement of the latch and coöperating means;

Fig. 10 represents a view similar to Fig. 9 in which the unlocking of the latch and coöperating locking means has completely 65 taken place and in which the separation of the bolt and latch has partially taken place; and

Fig. 11 represents an elevation of the actuating key.

Referring to the annexed drawings, I provide a suitable casing or main support 1 provided with a front cover 2 adapted to be secured to the main portion 1 by means of small tongues, not shown, struck up from the material of the cover 2 and inserted through the slots 3 of the main casing 1 and bent over back of said main casing 1. Suitably mounted upon said main casing 1 is a stud or pin 4 adapted to project through 75 the eye 5 of a keyhole formed in the cover 2, said keyhole having a slot portion 5'. The stem of the key 6 is adapted to be inserted through the eye 5 upon the pin 4, the slot 5' receiving the shank 6' of said key 85 provided with bits hereinafter fully described, for actuating the bolts, tumblers and other allied mechanism hereinafter fully described.

Supported upon the casing 1 immediately above the cover 2, is a rail 7 formed with a horizontal longitudinally disposed slot 8, in which a vertically disposed bolt arm 9 carrying a horizontal, longitudinally disposed bolt 10 is adapted to play. Said 90 rail 7 is formed adjacent its other end with a hole 11 through which a vertically disposed bolt 12 formed with a head portion 13 is adapted to play. Said head member 13 is formed with a laterally disposed slot 14 intersecting one side thereof and of a greater width at the bottom, indicated by the ordinal 16, than it is at the top, indicated by the ordinal 15, Fig. 6. The head 13 thus formed is adapted to act as a latch 105 and to coöperate with locking mechanism

formed upon the outer end of the bolt 10. This coöperation is effected by reason of the fact that said outer end of the bolt 10 is of a shape plainly shown in cross-section in Fig. 4, the ordinal 17 denoting the tapered shoulders thereof. These tapered shoulders coöperate with similarly tapered walls 14' of the opening 14, so that when said shoulders 17 and walls 14' are alined, and the bolt 10 and bolt 12 are in the position shown in Fig. 1, the latch 13 and bolt 10 can not be separated.

It is evident from the mechanism hereinbefore described that, in order to unlock the mechanism when it is in the position shown in Fig. 1, it will be necessary first to raise the bolt 12 so that the locking mechanism 17 of the bolt 10 can be freed from the narrow portion 15 of the slot 14 in the latch 13 and then, having thus potentially unlocked the mechanism, positively separating the bolt 10 and latch 13, to the position shown in Fig. 2. The detail of the mechanism for thus actuating the bolts 10 and 12 will now be described.

There is secured to the bottom of the bolt 12, a plate 18 having a notched front edge indicated by the several portions 19, 20 and 21. The bit 24 of the key shank 6' is adapted to actuate said plate 18 by means of acting upon the notched portions 19, 20 and 21, proper alinement and guides for the consequent actuation of the bolt 12 being furnished by the pin 22 secured in the case 1 and adapted to play in an elongated slot 23 formed in bolt 12. A further suitable alinement is provided by means of the pin 25 secured to the case 1 and adapted to play in the slot 26 formed in the plate 18. There is carried upon the plate 18 a projection or stump 18', whose purpose will now be described in detail. Before the key bit 24 can play upon the plate 18, it is necessary that the proper coöperative actions of a set of tumblers 27 now to be described, shall take place. There are provided any desired number of tumblers 27 in this set and, for purposes of illustration, I have shown a set of two tumblers 27 in the accompanying drawing. These tumblers are pivoted upon the pin 25 and are resiliently held by means of bent wire springs 31 secured to said tumblers in the manner plainly shown in the accompanying drawings and bearing at one end upon a pin 32 secured in case 1. These tumblers are provided with communicating slots 28, 29 and 30. They are also provided with notched or cam side portions 27'. Coöperating bits 33 formed upon the shank 6' of the key 6 adjacent to bit 24 and above the same, are adapted to play upon the tumbler notches 27', the several tumblers of the set being unequally actuated, as will be readily understood. During a complete actuation

of the tumblers 27, the stump 18' secured to the plate 18 is adapted to travel from the slot portion 28 to the slot portion 29 or vice versa, and through the intermediate slot portion 30. These slot portions 30 of the several tumblers of a set form one continuous vertical aperture so that it is evident that the key-bits 33 must actuate the several tumblers the exact distances required in order that the stump 18' may pass through all of the said slot portions 30 simultaneously. It is evident that when the lock is in a closed position and it is desired to unlock the same, the key will occupy the position relative to the plate 18 and the tumblers 27, shown in Fig. 1. The actuation of the key to the position shown in Fig. 9 will result in the contact of the bit 24 and the upper wall of notch 20 and in the partial vertical actuation of the bolt 12 plainly shown in said figure and the actuation of the tumblers 27 to the point where the stump 18' is passing through the slot portions 30, assuming that the key-bits 24 and 33, and the notches 19, 20 and 27 have been properly coöordinated. A further actuation of the key will result in the bit 24 further pushing against the upper wall of the notch 20 of the plate 18 and moving the plate 18 and bolt 12 to the position plainly shown in Fig. 2. This has resulted in the potential unlocking of the latch 13 and the coöperating locking members 17 on bolt 10. It is now necessary to positively separate the bolt 10 and latch 13. This is effected by the mechanism now to be described.

Guided upon the case 1 by means of slots 35 in which pins 36 secured to said case are adapted to play, is a movable plate 34 formed with notches 37, 38 and 39 adapted to coöperate with the bit 24 of the key 6. When the bolt 10 and latch 13 are in the position where the bolt 10 is in the wider portion 16 of the slot 14, i. e., potentially unlocked, then the bit 24 is adapted to pass the notch 37 of the plate 34 and intersect the far wall of the notch 38 and move the plate 34 to the left, Figs. 2 and 7, until said bit escapes from the notch 38 and is freed from the plate 34 through the notched portion 39. This action takes place, if the proper coöordination is effected between the bits 33 of the key and notches 41' and slots 42, 43 and 44 of a set of tumblers 41, the proper actuation and coöordination of said tumblers resulting in the movement of a projection or stump 40 secured to the plate 34 from position 42 to position 43, through intermediate position 44. The relative arrangement and actuation of this set of tumblers is similar to that of the set of tumblers 27 heretofore described. These tumblers are also resiliently held by means of bent wire springs 45 bearing upon pin 46 se-

cured to the case 1. It is now evident that, if the movement of the plate 34 is communicated to the bolt arm 9, the bolt 10 may be moved away from the latch 13 from 5 which it is potentially separated, to the position shown in Fig. 2. This connection is effected by the mechanism now to be described. A rack segment 47 is formed upon the upper edge of the plate 34 and the 10 same is gear connected to a pinion 48 mounted upon a pin 49 secured to the case 1. This pinion 48 meshes with a smaller pinion 50 secured to the face of a pinion 52, both of which are mounted upon a pin 51 15 secured to the case 1. This pinion 52 meshes with a second rack segment 53 secured to a plate 54 in turn secured to a plate 55 to one end of which also the bolt arm 9 is secured. These plates 54 and 55 20 are secured to the case 1 by a pin 56 and are movable thereacross and guided thereon by means of said pin and slots 57 formed in said plates 54 and 55.

Of course, the lock hereinbefore described 25 and hereinafter claimed and shown in the accompanying drawings, may be utilized to secure any appropriate article from unwarranted interference and a conventional form of such articles is indicated by the 30 ordinal 58, Fig. 8. It is found that the lock will very conveniently lend itself to the proper securing of automobile parts.

It is evident from the accompanying drawing that the locking of the mechanism 35 will be the reverse of that which has just been described, the sets of tumblers 41 and 27, respectively, being in such position that said locking operation results in the passage 40 of the stumps 40 and 18', respectively, from the slots 43 to the slots 42 and from the slots 28 to the slots 29, respectively, through the intermediate slots 44 and 30, respectively, in sequence, the relation of the notches 39, 38 and 37, and 21, 20 and 19, being such 45 that, in sequence, the bit 24 will pass the notch 39, intersect the far wall of the notch 38, move the plate 34 to the right, then pass the notch 37 and the notch 21, intersect the far wall of the notch 20 and move the plate 50 18 downwardly, and then pass the notch portion 19, the whole resulting in the movement of the bolt 10 and latch 13 to the 55 relative positions plainly shown in Fig. 1 and the possible release of the key stud 6' from the lock through the eye 5 and slot 5'.

What I claim is:

1. A lock comprising, a main support; a vertically movable bolt mounted upon said support and provided at the top with a 60 head formed with a laterally disposed slot adapted to serve as a keeper; a second bolt horizontally movably mounted upon said support and formed with locking means adapted to interlock with said keeper; means 65 for actuating said two bolts; and means con-

trolling the functioning of said actuating means upon said bolts.

2. A lock comprising, a main support, a bolt movably mounted upon said support; a second bolt movably mounted upon said support, said bolts having paths of movement in diverse directions and being formed with coöperating interlocking elements; and a key for actuating said bolts having two sets of bits, the connections between said key and 70 bolts including a pair of notched plates movably mounted upon said support and respectively connected to said bolts, one set of the key bits being adapted to actuate said plates, and two sets of tumblers mounted 75 upon said support, adapted to be actuated by the other set of key bits, and respectively controlling the actuation of said plates by the key.

3. A lock comprising, a main support, a bolt movably mounted upon said support; a second bolt movably mounted upon said support, said bolts being independently movable and having paths of movement in diverse directions, said bolts being formed 85 with coöperating interlocking elements; and a key for actuating said bolts having two sets of bits, the connections between said key and bolts including a pair of notched plates movably mounted upon said support 90 and respectively connected to said bolts, one set of the key bits being adapted to actuate said plates in sequence, and two sets of tumblers mounted upon said support, adapted to be actuated by the other set of key bits 95 in sequence, and respectively controlling the actuation of said plates by the key.

4. A lock comprising, a main support; a bolt movably mounted upon said support and provided at one end with a slotted head 105 forming a latch; a key for actuating said bolt; means controlling the actuations of said key; a notched plate movably mounted upon said support and adapted to be actuated by said key; means controlling the last 110 named actuations of said key; a second bolt movably mounted upon said support and formed with locking means coöperating with said latch; and gear elements connecting said plate and said second bolt.

5. A lock comprising, a main support; a bolt movably mounted upon said support and provided at one end with a slotted end forming a latch; a key for actuating said bolt; a tumbler pivotally mounted on said 120 support and controlling the actuations of said key; a notched plate movably mounted upon said support and adapted to be actuated by said key; a tumbler controlling the last 125 named actuations of said key; a second bolt movably mounted upon said support and formed with locking means coöperating with said latch; a rack segment secured to said second bolt; means guiding the movements of said segment; a rack segment formed 130

upon said notched plate; and pinions disposed intermediately of said rack segments.

6. A lock comprising, a main support; a vertically-movable bolt mounted upon said support and provided at the top with a head formed with a laterally disposed slot adapted to serve as a keeper; a second bolt horizontally-movably mounted upon said sup-

port and formed with locking means adapted to interlock with said keeper; means for actuating said two bolts; and two sets of means respectively controlling the functioning of said actuating means upon said bolts. ¹⁰

Signed by me, this 12th day of April, 1919.

HENRY D. GRIMES.
